UNITED STATES PATENT OFFICE.

FRANKLIN L. BARBER AND EDWIN W. WEBB, OF CHICAGO, ILLINOIS, ASSIGNORS TO STANDARD CAR TRUCK COMPANY, OF CHICAGO, ILLINOIS, A CORPORATION OF NEW JERSEY.

SIDE BEARING FOR CARS.

1,228,280.

Specification of Letters Patent.

Patented May 29, 1917.

Application filed February 21, 1916. Serial No. 79,586.

To all whom it may concern:

Be it known that we, FRANKLIN L. BARBER and EDWIN W. WEBB, citizens of the United States, residing at Chicago, in the 5 county of Cook and State of Illinois, have invented certain new and useful Improvements in Side Bearings for Cars; and we do hereby declare the following to be a full, clear, and exact description of the invention, such as will enable others skilled in 10 the art to which it appertains to make and use the same.

Our invention has for its object to provide an improved side bearing for railway 15 cars; and, to such ends, generally stated, the invention consists of the novel devices and combinations of devices hereinafter described and defined in the claim.

In the accompanying drawings, which 20 illustrate the invention, like characters indicate like parts throughout the several views.

Referring to the drawings,

Figure 1 is a view, partly in plan and 25 partly in horizontal section, of the improved side bearing, some parts being removed;

Fig. 2 is a view, partly in side elevation and partly in vertical section, some parts being removed;

Fig. 3 is a view, partly in end elevation and partly in vertical section, taken on the 30 line $x^3 x^3$ of Fig. 2;

Fig. 4 is an edge elevation of the improved key;

Fig. 5 is an end elevation of the same; 35 and

Fig. 6 is a detail view in section taken on the line $x^6 x^6$ of Fig. 4.

The numeral 1 indicates a cast metal housing 40 provided with suitable reinforcing ribs and having integrally formed therewith a flanged base adapted to be riveted, bolted, or otherwise rigidly secured to the ends of a truck bolster. In the side walls of the 45 housing, are formed bearing hubs 2 in which are mounted the ends of a pair of horizontally spaced heavy pins 3. On the intermediate portion of each pin 3, is loosely journaled a roller 4. The upper surfaces of 50 these rollers 4 are located at the same altitude and extend above the upper top surface of the housing. The base of the housing, just below each roller 4, is cut away so that sand and dirt may work downward out of

the housing, it being assumed, of course, 55 that the truck bolster would have some provision, such as a passage, to permit the precipitation of the sand and dirt.

The bearing hubs 2 hold the pins 3 against lateral displacement, but are open at their 60 ends to permit endwise displacement thereof. Bevel stop lugs 5 are integrally formed with one of the side walls of the housing and project upward, one into each of the 65 bearing hubs 2, on the respective side of the housing. One end of each pin 3 is beveled at 6 and these beveled surfaces engage the stop lugs 5, prevent endwise displacement of the pins 3 through the respective side 70 wall of the housing and also hold said pins against rotation.

To hold the pins 3 against endwise displacement, away from the stop lugs 5, we provide for each of said pins an L-shape key 7, the body of which is segmental in 75 cross section. The body of each key 7 is mounted in a correspondingly formed key seat 8. These key seats 8 are formed, one in the internal wall of each bearing hub 2 and extend completely therethrough. The 80 inner ends of the key seats 8 extend into recesses 9 formed in the respective side wall of the housing and which recesses form lateral extensions of the key seat 8 to receive the short ends of the key 7 and hold the 85 same against outward endwise displacement. The pins 3 hold the keys 7 against lateral 90 displacement and it will be noted that the outer faces of the keys 7 have the same curvature as the internal walls of the bearing hubs 2 to receive the pins 3.

In assembling the improved side bearing, the keys 7 are first placed in the key seats 8 with their short ends extending into the recesses 9. The pins 3 are next inserted into 95 the bearing hubs 2 in which the key seats 8 are formed and thereby hold the keys 7 against lateral displacement. The rollers 4 are then held within the housing 4, one in axial alinement with each pin 3. Said pins 100 3 are then moved endwise through the rollers 4 and into the other bearing hubs 2 with their bevel surfaces 6 in engagement with the stop lugs 5. The outer projecting ends of the keys 7 are then upset over the adjacent ends of the pins 3, which hold the same against endwise displacement, away from the stop lugs 5.

What we claim is:—
A side bearing for cars comprising a housing having in its side walls bearing hubs, a pin mounted in the bearing hubs, a 5 roller journaled on the pin, a key seat formed in the internal wall of one of the bearing hubs and extending laterally into the respective side wall of the housing, and an L-shape key mounted in the key seat, the 10 outer end of the key adapted to be bent over the adjacent end of the pin, the body

of the key being curved to form a continuation of the internal wall of the respective bearing hub across its key seat and to fit the contour of the pin.

15

In testimony whereof we affix our signatures in presence of two witnesses.

FRANKLIN L. BARBER.
EDWIN W. WEBB.
